Inventor,
ISAAC N. BEERY, JR.

UNITED STATES PATENT OFFICE.

ISAAC N. BEERY, JR., OF HARRISONBURG, VIRGINIA.

ABDOMINAL SUPPORTER.

1,366,897.

Specification of Letters Patent. Patented Feb. 1, 1921.

Application filed April 19, 1920. Serial No. 374,976.

To all whom it may concern:

Be it known that I, ISAAC N. BEERY, Jr., a citizen of the United States, residing at Harrisonburg, in the county of Rockingham and 5 State of Virginia, have invented new and useful Improvements in Abdominal Supporters, of which the following is a specification.

The object of my present invention is the 10 provision of an abdominal supporter that is, at once, extremely simple and inexpensive in construction and highly efficient in operation, and the latter without being uncomfortable, irrespective of whether the wearer 15 is standing, stooping or is seated.

The invention also contemplates the provision of an abdominal supporter of such construction that the elastic members, which are the only parts likely to wear out after a 20 short period of use, may be expeditiously and easily replaced by new elastic members at small expense and without the employment of skilled labor.

To the attainment of the foregoing, the 25 invention consists in the improvement as hereinafter described and definitely claimed.

In the accompanying drawings, hereby made a part hereof:

Figure 1 is a perspective of the abdominal 30 supporter constituting the best practical embodiment of my invention of which I am cognizant.

Fig. 2 is a front elevation of the front member of the supporter.

Fig. 3 is a rear elevation of the back member.

Fig. 4 is an elevation of one of the elastic connecting members of the supporter; there being by preference, four of said members; 40 two at each side of the supporter.

Similar numerals of reference designate corresponding parts in all of the views of the drawings.

The front member 1 and the back member 45 2 of the supporter are preferably formed of thin and pliable leather in about the shapes and comparative sizes illustrated. On its forward side and at points adjacent to its ends the member 1 is equipped with buckles 50 3, the said buckles being preferably, though not necessarily, carried at the ends of a strap 4 that is stitched or otherwise permanently attached to the member 1 at the forward side thereof.

55 At its rear side and at points spaced from

its ends the back member 2 is provided with buckles 5, these buckles being preferably carried at the ends of a strap 6^a that is permanently fastened to the rear side of the member.

As before indicated, the supporter also includes elastic connecting members 6, preferably four in number, and disposed two at each side of the supporter. The said members 6 are of even length and width and 65 when four are employed, two at each side of the supporter are adjustably connected to the front and back members through the medium of the buckles 3 and 5, respectively. Manifestly when the supporter is in use, the 70 said elastic connecting members or straps 6 are adapted to lay in the hollows of the hips of the wearer in which positions they will adequately retain the members 1 and 2 in proper working position and will effectively 75 hold the same against upward movement when the wearer is sitting or is in a stooping posture, and this without subjecting the wearer to any discomfort whatever.

By virtue of the elastic members or straps 80 6 being employed in pairs, as is preferred, they lend ample strength and resiliency to the supporter, and permit of the same being readily adjusted to persons of different sizes and shapes, and when any one or more of 85 the members 6 become worn the same may be expeditiously and easily removed and as readily replaced with new elastic members.

Also by virtue of its peculiar shape and construction my invention reduces to a minimum the pressure upon the hips and fixes 90 the pressure upon the abdomen, whereas other supports of which I have knowledge, do not adequately produce this effect. Especially is this true when worn by a slender 95 person, in which case the pressure is usually greater upon the hips than upon the abdomen.

Having described my invention, what I claim and desire to secure by Letters 100 Patent is:—

An abdominal supporter comprising a front member of thin pliable material, a back member, buckles carried at the front of the front member and spaced from the ends 105 and edges thereof, buckles carried at the rear side of the back member and spaced from the ends and edges thereof, and elastic members adjustably secured in the buckles and extending outside of and between and con- 110

necting the front and back members at the sides of the supporter; the buckles of the front member being connected to the ends of a strap permanently attached to the front 5 side of the front member, the buckles of the back member being connected to the ends of a strap permanently attached to the rear

side of said member, and the interposed elastic members being arranged in pairs, one pair at each side of the supporter and 10 made up of side by side straps.

In testimony whereof I affix my signature.

ISAAC N. BEERY, JR.
